US00D725037S

(12) **United States Design Patent**
Norman et al.

(10) **Patent No.:** US D725,037 S
(45) **Date of Patent:** ** Mar. 24, 2015

(54) **MOTOR ASSEMBLY HOUSING FOR A CONSTRUCTION KIT**

(71) Applicant: **Innovation First, Inc.**, Greenville, TX (US)

(72) Inventors: **David Anthony Norman**, Greenville, TX (US); **Robert H. Milmitch, III**, Rowlett, TX (US); **Raul Olivera**, Greenville, TX (US); **Douglas Michael Galletti**, Allen, TX (US); **Gregory James Lavender**, Rockwell, TX (US); **Jeffrey Russel Waegelin**, Rockwell, TX (US); **James Anthony Trzaskos**, Greenville, TX (US); **Kelvin Gunnar Frank**, Greenville, TX (US); **Jason Alan Weihman**, Greenville, TX (US); **Thomas Charles Glick**, Greenville, TX (US); **Arthur Philip Dutra, IV**, Greenville, TX (US); **John Edward Vielkind-Neun**, Greenville, TX (US); **Paul David Copioli**, Rockwell, TX (US)

(73) Assignee: **Innovation First, Inc.**, Greenville, TX (US)

(**) Term: **14 Years**

(21) Appl. No.: **29/488,288**

(22) Filed: **Apr. 17, 2014**

(51) LOC (10) Cl. **13-01**

(52) U.S. Cl.

USPC **D13/112**

(58) **Field of Classification Search**

CPC F02B 63/04
